UNITED STATES PATENT OFFICE.

NATHAN H. DAVIS, OF PHILADELPHIA, PENNSYLVANIA, ASSIGNOR OF ONE-HALF TO LEWIS C. GRATZ, OF SAME PLACE.

CAR-SPRING.

SPECIFICATION forming part of Letters Patent No. 364,492, dated June 7, 1887.

Application filed February 24, 1887. Serial No. 228,708. (No model.)

To all whom it may concern:

Be it known that I, NATHAN H. DAVIS, a citizen of the United States, residing in the city and county of Philadelphia, State of Pennsylvania, have invented a new and useful Improvement in Car-Springs, which improvement is fully set forth in the following specification and accompanying drawings, in which—

Figure 1 represents a top or plan view of the car-spring embodying my invention. Fig. 2 represents the central vertical section thereof.

Similar letters of reference indicate corresponding parts in the two figures.

My invention consists of a car-spring formed of spring-plates constructed of wrought metal, having openings with inwardly-projecting flanges around said openings, springs which are interposed between the plates and fitted to said flanges, and a cup which is connected 20 with one of the spring-plates by means of a bolt, whereby a strong, durable, and inexpensive spring is produced, as will be herein-after more fully set forth.

Referring to the drawings, A represents upper and lower spring-plates and B represents the springs which are fitted between said plates. In each plate is a series of openings, C, the walls of which have inwardly-projecting flanges D, which enter the ends of the 30 springs B, whereby displacement of the springs from said plates is prevented. In the center of one of the plates, A, is an opening in which is fitted a socket or cup, E, the base of which is perforated for the passage of the bolt F, which also passes through the opening in the other plate, and has its head bearing against said plate and occupying the recess G therein. The threaded end of the bolt projects into the 35 cup E and carries the nut G', which, as will be seen, occupies the cup E.

The plates A are formed of wrought metal, and the flanges D are produced by squeezing,

punching, pressing, or otherwise working the metal, said flanges serving to strengthen the walls of the openings C, and consequently the 45 plates themselves, whereby the plates are strong and durable, and as they may be made of comparatively light metal the weight and expense of the car-spring are reduced, the employment of such metal in the manufacture of 50 spring-plates A avoiding the delay incident to the formation of such plates of malleable iron owing to the long time necessarily required in the formation of cast metallic plates and the conversion of the same into malleable 55 iron.

I am aware that it is not new to make spring-plates of wrought metal having depressions therein; but in my invention the spring-plates are primarily punched to form the openings C, and said openings are then flanged, whereby their walls and, consequently, the corners of the plates are greatly stiffened without adding to the weight of the plates, while the plates are of reduced weight, owing to the 60 openings C. The spring-plates, with their openings and flanges, form the subject-matter of an application for Letters Patent, Serial No. 228,707, filed by me of even date herewith.

Having thus described my invention, what 70 I claim as new, and desire to secure by Letters Patent, is—

A car-spring consisting of the springs B, the top and bottom plates A, the socket E, the bolt F, and the nut G, said plates being 75 formed of wrought metal, with openings C, having flanges D around the walls thereof, said parts being combined and operating substantially as described.

NATHAN H. DAVIS.
